UNITED STATES PATENT OFFICE.

DANIEL S. TROY, OF MONTGOMERY, ALABAMA.

CUT-OFF FOR CISTERNS.

SPECIFICATION forming part of Letters Patent No. 308,861, dated December 2, 1884.

Application filed May 8, 1884. (No model.)

To all whom it may concern:

Be it known that I, DANIEL S. TROY, of 5
Montgomery, in the county of Montgomery
and State of Alabama, have invented a new
and Improved Cut-Off for Cisterns, of which
the following is a full, clear, and exact de-
scription.

The object of my invention is to provide a
new and improved device for automatically
10 preventing the rain-water from passing into
the cistern until after the roof has been
washed off.

The invention consists in the combination,
with a barrel or tank having an apertured
15 horizontal partition a short distance below
the top, of a float held below the partition,
and of an overflow-pipe connecting the upper
part of the tank or barrel with the cistern.

Reference is to be had to the accompanying
20 drawings, forming a part of this specification,
in which similar letters of reference indicate
corresponding parts in both the figures.

Figure 1 is a longitudinal sectional elevation
of my improved cut-off for cisterns. Fig.
25 2 is a sectional plan view of the same on the
line *x x*, Fig. 1.

A tank, A, such as a barrel or other suit-
able receptacle, is provided about six inches
30 from its top with a transverse partition, B,
provided with an aperture, C. The water-
inlet pipe D, or leader from the roof, is held
in the head A' of the barrel or top of the
35 tank. A float, E, adapted to close the aper-
ture C, is held in the barrel in the part be-
low the partition B. An overflow-pipe, F,
leads from that part of the barrel or tank
above the partition B to the cistern G. The
40 barrel or tank A is provided at its bottom
with an outlet-cock, H. The water flows
from the pipe D into the barrel or tank and
collects in the bottom of the same, and as the
level of the water rises the float E rises and
45 then closes the aperture C by being pressed
by the water against the under side of the
partition B. The water then flows through
the pipe F into the cistern. The water that
is first collected on the roof, and which has
50 washed off the roof and contains the impuri-
ties, &c., that were on the roof, is collected
in the tank or barrel, and only the clean and
pure water can pass into the cistern. When
it stops raining, the water in the barrel or
tank is drawn off through the cock H.

My improved cut-off prevents any impuri-
ties being washed from the roof into the cis- 55
tern. The impurities floating in the lower at-
mosphere and brought down by the rain when
it begins to fall, as well as the impurities
collected on the roof, are carried into the
barrel or receptacle. The quantity of water 60
required to collect these impurities varies in
different localities; but by using one or more
barrels or receptacles connected by a pipe to
the one containing the cut-off the storage
room for the impure water may be indefi- 65
nitely increased, so that only pure rain-water
will flow into the cistern. Snow-water is
always impure, because the snow mixes with
the impurities which are on the roof when
the snow falls, and also absorbs impurities 70
from the atmosphere while it remains on the
roof, and these impurities are in the water
formed by the melting snow; consequently,
when snow is melting the cock H should be
left open, so that none of the water can enter 75
the cistern; but by use of the cut-off abso-
lutely-pure rain-water can be secured at all
seasons when there is not snow on the roof.
The inlet-pipe D, or leader from the roof,
should enter the head of the barrel or top of 80
the tank near one side, so that the impact of
the falling water may not disturb the float E
when the barrel or tank is full.

Having thus described my invention, what I
claim as new, and desire to secure by Letters 85
Patent, is—

1. A cut-off for cisterns made substantially
as herein shown and described, and consist-
ing of a tank or vessel connected by an over-
flow-pipe with the cistern, and provided with 90
a valve which automatically closes an open-
ing in the tank or vessel, to prevent the water
that has collected in the tank from mixing
with the water that is to pass into the cistern,
as set forth. 95

2. In a cut-off for cisterns, the combination,
with the barrel or tank A, of the horizontal
partition B, having an aperture, C, the over-
flow-pipe F, leading from the part above the
partition to the cistern, the float E, and the 100
cock H, substantially as herein shown and
described.

DANIEL S. TROY.
